UNITED STATES PATENT OFFICE

LOUIS VISCOLOSI, OF PROVIDENCE, RHODE ISLAND, ASSIGNOR TO THE ESMOND MILLS,
OF ESMOND, RHODE ISLAND, A CORPORATION OF RHODE ISLAND

LOOM

Application filed January 30, 1929. Serial No. 336,234.

My invention relates to improved means for weaving headings or other transversely disposed nonornamental areas between the desired fancy patterns in looms having a jacquard or other fancy pattern mechanism. This becomes highly desirable when it is desired to remove the completely woven cloth roll and substitute a new one therefor and eliminate spoiling a complete pattern cloth insert such as a woven blanket by cutting it in the middle for this purpose. My invention makes it possible to weave a short irregular heading between each roll so that when the cloth is cut for removal of the roll, no complete blanket or other cloth unit will be spoiled.

My invention is particularly applicable to Jacquard looms and comprises manually settable means to automatically reverse the direction of rotation of the card cylinders for a predetermined number of cards and to automatically move the card cylinders forward up to and including the first card reversed and if desired, continuously repeating this cycle and automatically at the completion of one cycle or if desired after a predetermined number of cycles cutting out the action of this supplemental mechanism to permit the card cylinders to continuously rotate forward to weave the desired number of blankets or other cloth units. So far as I am aware I am the first to provide a mechanism of this type on which the only manual operation necessary is to set the supplemental mechanism substantially at the end of a complete pattern just prior to weaving a heading and which will, after a heading of the desired length has been woven therein, automatically cut out the action of the supplemental mechanism to permit the loom to go ahead to automatically weave the desired roll of cloth.

My invention further relates to the specific means I employ for this purpose which also permits if desired, the oppositely disposed card cylinder rotating pawls to be set in a neutral position so that the card cylinder may be turned forwards or backwards manually or otherwise any desired number of cards.

A further object of my invention is to pro-

vide a supplemental mechanism for this purpose which will not only reverse the run of the pattern cards at any predetermined point and automatically resume the original direction of run of the cards up to said point having complete semi-reversal and semi-forward movement cycles but which will also effect any desired multiple of such cycles, will prevent the waste of woven material, save time and reduce the labor of the attendant without any structural change of the jacquard portion or the weaving portion of the loom.

These and such other objects of my invention as may hereinafter appear will be best understood from a description of the accompanying drawings which illustrate an embodiment thereof.

In the drawings, Fig. 1 is a diagrammatic side elevation of certain parts of a double card cylinder Jacquard loom having my invention attached, showing diagrammatically the two four card cylinders, the oppositely disposed pawls for turning said cylinders in opposite directions, and my supplemental mechanism including the means I preferably employ to actuate it, preferably through the medium of the griff lever, with my supplemental mechanism functioning to raise the lower card cylinder pawls in a position to reverse the direction of rotation of the card cylinders, substantially at the beginning of the reversing portion of the cycle.

Fig. 2 is a plan view of the cam means and adjacent reducing train of gearing I preferably employ.

Fig. 3 is a diagrammatic side elevation similar to Fig. 1 with my supplemental mechanism functioning to lower the upper pawls to a position to rotate the card cylinders forwards substantially at the beginning of the forward movement portion of the supplemental mechanism cycle.

Fig. 4 is a side elevation of the cam, ratchet and reducing train of gearing looking outwards from the inside of the loom.

In the drawings, wherein like characters of reference indicate like parts throughout, 10 generally indicates the frame of a loom. 12 indicates a portion of the frame of the jacquard mechanism thereof. The card cylin-

ders 14, which rotate the cards 17, are suitably rotatably mounted on a portion of the jacquard frame 12 and are provided with suitable means to operate them through the medium of the rods 13. Suitable oppositely disposed pawls or hooks 16 and 18 are provided for turning said cylinders 14 in opposite directions on the outward movement of the reciprocating cycle thereof. In the embodiment shown, said pawls comprise the upper pawls 16 pivotally mounted on the jacquard frame 12 above said cylinders 14 adapted to contact the cylinder heads 15 of the cylinders to cause a quarter forward revolution thereof on each outward movement of the cylinder. The lower pawls 18 are also suitably pivotally mounted on said jacquard frame 12 below said cylinders and are adapted to contact the cylinder head 15 of each cylinder to cause a quarter reverse revolution of each cylinder on each outward movement of the cylinder in its reciprocating cycle. If desired, a single cylinder jacquard may be employed in place of the double cylinder jacquard shown. In the double cylinder jacquard shown however, the reciprocating cycles of the card cylinders are alternate. In order simultaneously to move the upper pawls 16 into and the lower pawls 18 out of operative position and vice versa I provide suitable link means 20 pivotally attached to the outer ends of said pawls preferably through the medium of the holes 22 formed therein. The jacquard mechanism hitherto described, particularly the upper pawls 16 thereof, are commonly used in most Jacquard looms today and I am aware that others have also provided cooperating lower pawls 18 and some have provided means 20 to provide simultaneous opposite movement thereof, and also some have provided means to simultaneously move the upper and lower pawls 16 and 18 from operative to inoperative positions. So far as I am aware, however, no one has hitherto shown the specific means about to be described for this purpose which forms the subject matter of my invention.

I provide the cam 24 suitably rotatably mounted, by means of the pivot shaft 25, on a suitable portion of the loom frame 10. Said cam 24 has a portion 26, preferably substantially a semi-circle of a relatively small radius, and a portion 28 preferably substantially a semi-circle of a relatively larger radius. Said portions 26 and 28 are connected by the inclined portion 30 leading from the portion of small radius 26 to the portion 28 of greater radius and the preferably radial portion 32 joining the portion 28 of larger radius to the portion 26 of small radius in the direction of the cam's rotation. To suitably move said connected pawls 16 and 18, I provide the vertically reciprocal support 34 having the upper end 36 thereof suitably pivotally attached to the lower pawl 18 by means of the pivot

pin 38 or otherwise. Where two card cylinders are employed, the upper end of said rod 34 is formed of a U-shape having each U-leg 40 thereof suitably pivotally joined to each respective lower pawl 18 by means of the respective pivot pins 38, and each leg 40 thereof suitably constrained to reciprocate in a vertical direction by means of the guideways 42 suitably mounted on the jacquard frame 12. The lower end 44 of said support 34 rests on the periphery of the cam 24 and is preferably provided with the rotatable roller 46 adapted to travel over said periphery. It is thus obvious that when said end 44 rests on the semi-circle 28 of greater radius, it will raise up said lower pawls 18 to reverse the direction of rotation of the card cylinders on reciprocation thereof, and when said end 44 contacts the portion 26 of lesser radius on said cam 24 it will lower the connected upper pawls 16 to a position to rotate the card cylinders 14 forwards on reciprocation thereof.

To effect rotation of said cam 24 to permit the alternate bringing of the pawls 16 and 18 into operative position, I provide the ratchet 48, attached to said cam 24 preferably by being rigidly mounted on the said pivot shaft 25 on which said cam 24 is rigidly mounted.

In order to rotate said cam I preferably provide a pawl rod 50 having a lower pawl end 52 adapted to be moved to a position on suitable reciprocation of the rod 50 to rotate said ratchet 48 and integral cam 24. Said rod 50 preferably extends obliquely downwardly in a position to rotate said ratchet 48 and has the upper end thereof duly reciprocated in any suitable fashion, in the preferred embodiment by having the upper end 54 thereof suitably pivotally attached to a griff actuating lever 56 suitably pivoted to a portion of the jacquard frame 12, although if desired, the rod 50 may be obliquely reciprocated in any suitable manner. The griff actuating lever however, which raises the griff casing to lift the griff knives forms a very convenient means for this purpose.

I provide suitable means to automatically cut out the functioning of the supplemental means for bringing the pawls 16 and 18 into and out of operative relation. Such supplemental means comprises the support 34, cam 24, ratchet 48 and operating rod 50, to automatically move said actuating rod to inoperative position after a predetermined time to permit a continuous forward movement of the card cylinders 14 through the medium of the upper pawls 16 as usual. In order to better permit the weaving of a relatively large heading during a plurality of cam cycles, I preferably employ a reducing train of gearing to permit a predetermined number of cam cycles before said cam rotating means is automatically knocked off to inoperative position, and for this purpose I pref-

erably employ the reducing train of gearing 58. Said reducing train of gearing 58 is suitably mounted on a supporting bracket 60 suitably attached to a portion of the loom frame 10. The shaft 25 also has mounted thereon the relatively small gear 62 adapted to enmesh a relatively larger gear 64 suitably mounted on a shaft 66 which has also mounted thereon the relatively small gear 68, said shaft 66 being suitably mounted on said bracket 60. Said relatively small gear 68 is adapted to enmesh the relatively larger gear 70 suitably mounted on the shaft 72 also rotatably mounted on the bracket 60. In the embodiment shown, this reducing train of gearing operates in a ratio of thirty-six to one to permit thirty-six rotations of the cam 24 for one complete rotation of the last gear 70 in the reducing train. If desired, any gear in the reducing train of gearing 58 may consist of a change speed gear.

The preferred type of knockoff means shown comprises the knockoff pin 74 projecting axially from the last gear 70 in the reducing train 58, and the curved knockoff hook 76 having the outer end thereof suitably pivotally mounted through the medium of the pin 78 on the bracket 60 and having an inner inwardly curved portion 80 adapted to abut and knock off said actuating rod 50 on an upward movement of said knockoff hook 76 caused by contact with the knockoff pin 74. It is thus obvious that as said knockoff hook is raised, the curved portion 80 thereof will contact a curved portion 51 of said rod to move the lower pawl end 52 of said rod inwards out of contact with the ratchet 48. I also preferably provide the spring means 82 having one end 84 thereof suitably attached to the frame 10 and the opposite end 86 thereof suitably attached to the actuating rod 50 to move its pawl end 52 laterally out of contact with the ratchet 48 after it has been moved inwardly by the curved portion 80 of said hook 76.

As stated hitherto, the purpose of my invention is to provide a supplemental mechanism for inserting a heading between a continuous run of patterns while weaving, and for this purpose I break the continuous forward movement of the cylinder cards to weave the pattern by injecting into the system in place of the primary card cylinder forward rotating means, a supplemental and auxiliary means operative to continuously reverse the direction of rotation of the card cylinder for a predetermined number of cards and then to permit forward movement of the card cylinder up to the first card reversely rotated, and means to automatically cut out the operation of said auxiliary means after the completion of a cycle thereof to permit said primary forward driving means for the card cylinder to continuously rotate said cards forward to weave the pattern. In my pre-

ferred embodiment the means to automatically cut out the operation of said auxiliary means occurs after a predetermined plurality of cycles of said supplemental means. Thus in operation, where two card cylinders are employed, they are continuously reciprocated, moving in alternate directions by any suitable means such as those heretofore described and in the normal weaving of the pattern the upper pawls 16 are dropped to a position to contact the cylinder heads 15 to continuously rotate the card cylinders forward to weave the pattern. When it is desired to weave a heading, the operating rod 50 is moved to a position so that the pawl end 52 thereof will engage the ratchet 48 and this normally occurs at the period of the cam cycle shown in Fig. 1 when the portion 28 of larger radius of the cam contacts the lower end 44 of the support 34, to raise up the support 34 and lower pawls 18 to cause a reverse rotation of the card cylinders on reciprocation thereof. This will occur for a predetermined number of cards or until the semi-circle 26 of larger radius has passed the lower end 44 of the support 34 when said support 34 will drop by gravity to cause the lower end 44 thereof to contact the portion 26 of smaller radius of said cam 24, thus automatically lowering the lower pawls 18 out of contact with the cylinder heads 15 and automatically lowering the upper pawls 16 through the medium of the links 20 into a position to engage the cylinder heads 15 to cause the usual forward movement of the card cylinders 14. If the semi-circle 26 is of substantially equal time controlled length to the portion 28 of larger radius, it is obvious that the pawls 16 will rotate the card cylinders forward an amount substantially equal to the amount they have been reversed and namely to the same card at which the rearward rotation thereof commenced. Then if the actuating rod 50 is raised in a position to continuously actuate the ratchet 44 to move the cam 24 forwards, it is obvious that a new cam cycle will come into operation, the lower end 44 of the support 34 then riding up through the intermediate portion 30 of the cam to the portion 28 of larger radius thereof to permit the lower pawls 18 to again reverse the direction of rotation of the cylinders 14. It is also clear that for the desired number of cam cycles the cards will be first alternatively reversed a predetermined time and then alternately moved forward up to the reversal card, when, through the medium of the reducing gearing 58, after the desired number of cam cycles have been completed to weave the desired length of heading to cause one complete revolution of the lowest gear 70 in the reducing train of gearing 58, the knockoff pin 74 will raise the knockoff hook 76 to cause the curved portion 80 thereof to knock the pawl end 52 of the operating rod 50 inwards out

of contact with the ratchet 48, whereupon the spring 82 will move it laterally further out of contact to cause the primary card cylinder driving means, namely, the upper 5 pawls 16 to continuously rotate the card cylinders 14 forwards to weave the desired jacquard pattern. As stated hitherto, the knock-off means may be made to function at a completion of a single reverse and forward card cylinder movement cycle instead of a plurality of cycles by omitting the reducing train of gearing 58 and locating the knockoff pin 74 directly on the ratchet 48 or cam 24. As stated hitherto if desired, the support 34 may 10 be raised to a neutral position on the rising cam surface 30 to permit the jacquard card cylinders 14 to be manually turned in either direction to move the jacquard cards 17 backwards and forwards any desired amount.

20 It is thus apparent that I have provided a suitable auxiliary jacquard card rotating mechanism suitable for weaving headers between jacquard patterns of any desired length.

25 It is understood that my invention is not limited to the specific embodiment shown and that various deviations may be made therefrom without departing from the spirit and scope of the appended claims.

30 What I claim is:

1. In a loom, in combination, a jacquard mechanism including a frame, a griff actuating lever mounted thereon, a card cylinder mounted on said frame, means to reciprocate said card cylinder, two oppositely disposed pawls for turning said cylinder on reciprocation thereof pivotally mounted on the jacquard frame on opposite sides of said cylinder, link means pivotally joining 35 said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the connected upper pawl to a position to rotate the card cylinder forwards, a ratchet gear attached to said cam, a rod having the upper end thereof attached to and reciprocated by the griff actuating lever extending obliquely downwardly and having the lower end thereof terminating in a pawl and adapted to be moved to a position on reciprocation thereof to rotate said ratchet and attached cam, a train of reducing gearing actuated by said cam, and knockoff means for said reciprocating rod actuated on a complete rotation of the last gear in the reducing train of gearing after multiple revolutions of said cam to automatically permit continuous forward movement of the card cylinder.

2. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the connected upper pawl to a position to rotate the card cylinder forwards, a ratchet gear attached to said cam, a rod having the upper end thereof attached to and reciprocated by the griff actuating lever extending obliquely downwardly and having the lower end thereof terminating in a pawl and adapted to be moved to a position on reciprocation thereof to rotate said ratchet and attached cam, a train of reducing gearing actuated by said cam, and knockoff means for said reciprocating rod actuated on a complete rotation of the last gear in the reducing train of gearing after multiple revolutions of said cam to automatically permit continuous forward movement of the card cylinder.

3. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the connected upper pawl to a position to rotate the card cylinder forwards, a ratchet gear attached to said cam, a rod having the upper end thereof attached to and reciprocated by the griff actuating lever extending obliquely downwardly and having the lower end thereof terminating in a pawl and adapted to be moved to a position on reciprocation thereof to rotate said ratchet and attached cam, a train of reducing gearing actuated by said cam, and knockoff means for said reciprocating rod actuated on a complete rotation of the last gear in the reducing train of gearing after multiple revolutions of said cam to automatically permit continuous forward movement of the card cylinder.

tions of said cam to automatically permit continuous forward movement of the card cylinder.

2. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the connected upper pawl to a position to rotate the card cylinder forwards, a ratchet gear attached to said cam, a rod having the upper end thereof attached to and reciprocated by the griff actuating lever extending obliquely downwardly and having the lower end thereof terminating in a pawl and adapted to be moved to a position on reciprocation thereof to rotate said ratchet and attached cam, a train of reducing gearing actuated by said cam, and knockoff means for said reciprocating rod actuated on a complete rotation of the last gear in the reducing train of gearing after multiple revolutions of said cam to automatically permit continuous forward movement of the card cylinder.

3. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the connected upper pawl to a position to rotate the card cylinder forwards, a ratchet gear attached to said cam, a rod having the upper end thereof attached to and reciprocated by the griff actuating lever extending obliquely downwardly and having the lower end thereof terminating in a pawl and adapted to be moved to a position on reciprocation thereof to rotate said ratchet and attached cam, a train of reducing gearing actuated by said cam, and knockoff means for said reciprocating rod actuated on a complete rotation of the last gear in the reducing train of gearing after multiple revolutions of said cam to automatically permit continuous forward movement of the card cylinder.

- port having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the connected upper pawl to a position to rotate the card cylinder forwards, a ratchet gear attached to said cam, a rod having the upper end thereof attached to and reciprocated by the griff actuating lever extending obliquely downwardly and having the lower end thereof terminating in a pawl end adapted to be moved to a position on reciprocation thereof to rotate said ratchet and attached cam, a train of reducing gearing actuated by said cam, a knockoff pin projecting axially from the last gear in the train, a curved knockoff hook pivotally mounted on said frame adapted to be moved by said pin on a complete rotation of said last gear after multiple revolutions of said cam having an inwardly curved portion adapted to knockoff said actuating rod inwardly on upward movement thereof.

4. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining each cylinder pawl together, and a repeat mechanism comprising a cam rotatably mounted on the loom frame having a semi-circle of a relatively small radius and a semi-circle of a greater radius, a vertically reciprocable support having a split U-shaped upper end having each U-leg thereof attached to each respective lower pawl, and the lower end thereof resting on said cam, whereby when said end rests on the semi-circle of greater radius it will raise up said lower pawls to reverse the direction of rotation of the card cylinders, and when said end contacts the portion of lesser radius on said cam, it will lower the connected upper pawls to a position to rotate the card cylinders forwards, a ratchet gear attached to said cam, a rod having the upper end thereof attached to and reciprocated by the griff actuating lever extending obliquely downwardly and having the lower end thereof terminating in a pawl end adapted to be moved to a position on reciprocation thereof to rotate said ratchet and attached cam, a train of reducing gearing actuated by said cam, and knockoff means for said reciprocating rod actuated on a complete rotation of the last gear in the reducing train of gearing after multiple revolutions of said cam to automatically permit continuous forward movement of the card cylinder.
6. In a loom, in combination, a jacquard mechanism including a frame, a griff actuating lever mounted thereon, two rotatable card cylinders having cylinder heads rotatable in opposite directions rotatably mounted on said frame, means to alternately reciprocate said cylinders in opposite directions, a pawl pivotally mounted on each frame above each cylinder adapted to contact

its cylinder head to cause a quarter forward revolution thereof on each outward movement of the cylinder, a pawl pivotally mounted on said frame below each cylinder adapted to contact its cylinder head to cause a quarter reverse revolution thereof on each outward movement of the cylinder, link means pivotally joining the pawls of each cylinder together, and a repeat mechanism comprising a cam rotatably mounted on the loom frame having a semi-circle of a relatively small radius and a semi-circle of a greater radius, a vertically reciprocable support having a split U-shaped upper end having each U-leg thereof attached to each respective lower pawl, and the lower end thereof resting on said cam, whereby when said end rests on the semi-circle of greater radius it will raise up said lower pawls to reverse the direction of rotation of the card cylinders and when said end contacts the portion of lesser radius on said cam, it will lower the upper pawls to a position to rotate the card cylinders forwards, a ratchet gear attached to said cam, a rod having the upper end thereof attached to and reciprocated by the griff actuating lever extending obliquely downwardly and having the lower end thereof terminating in a pawl end adapted to be moved to a position on reciprocation thereof to rotate said ratchet and attached cam, a train of reducing gearing actuated by said cam, a knockoff pin projecting axially from the last gear in the train, a curved knockoff hook pivotally mounted on said frame adapted to be moved by said pin on a complete rotation of said last gear after multiple revolutions of said cam having an inwardly curved portion adapted to knock off said actuating rod inwardly on upward movement thereof.

4. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the upper pawl to a position to rotate the card cylinder forwards, a ratchet gear attached to said cam, pawl means to rotate said ratchet, means to actuate said pawl means to rotate said ratchet and attached cam, a reducing train of gearing actuated by said cam, and knock-off means for said pawl means actuated on a complete rotation of the last gear in the reducing train of gearing after multiple revolutions of said cam to automatically permit

ciprocable support having a split U-shaped upper end having each U-leg thereof attached to each respective lower pawl, and the lower end thereof resting on said cam, whereby when said end rests on the semi-circle of greater radius it will raise up said lower pawls to reverse the direction of rotation of the card cylinders and when said end contacts the portion of lesser radius on said cam, it will lower the upper pawls to a position to rotate the card cylinders forwards, a ratchet gear attached to said cam, a rod having the upper end thereof attached to and reciprocated by the griff actuating lever extending obliquely downwardly and having the lower end thereof terminating in a pawl end adapted to be moved to a position on reciprocation thereof to rotate said ratchet and attached cam, a train of reducing gearing actuated by said cam, a knockoff pin projecting axially from the last gear in the train, a curved knockoff hook pivotally mounted on said frame adapted to be moved by said pin on a complete rotation of said last gear after multiple revolutions of said cam having an inwardly curved portion adapted to knock off said actuating rod inwardly on upward movement thereof.

8. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the upper pawl to a position to rotate the card cylinder forwards, a ratchet gear attached to said cam, pawl means to rotate said ratchet, means to actuate said pawl means to rotate said ratchet and attached cam, a reducing train of gearing actuated by said cam, and knock-off means for said pawl means actuated on a complete rotation of the last gear in the reducing train of gearing after multiple revolutions of said cam to automatically permit

continuous forward movement of the card cylinder.

9. In a loom, in combination, a jacquard mechanism including a frame, a griff actuating lever mounted thereon, a card cylinder mounted on said frame having a cylinder head, means to reciprocate said card cylinder, a pawl pivotally mounted on said frame above said cylinder adapted to contact the cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining the outer ends of said pawls together, and a repeat mechanism comprising a cam rotatably mounted on the loom frame having a semi-circle of a relatively small radius and a semi-circle of a greater radius, a vertically reciprocable support having the upper end attached to the lower pawl and the lower end thereof resting on said cam, whereby when said end rests on the semi-circle of greater radius it will raise up said lower pawl to reverse the direction of rotation of the card cylinder and when said end contacts the portion of lesser radius on said cam, it will lower the upper pawl to a position to rotate the card cylinder forwards, a ratchet gear attached to said cam, pawl means to rotate said ratchet, means to actuate said pawl means to rotate said ratchet and attached cam, and knockoff means for said pawl means to automatically permit continuous forward movement of the card cylinder.

10. In a loom, in combination, a jacquard mechanism including a frame, two rotatable card cylinders having cylinder heads rotatable in opposite directions rotatably mounted on said frame, means to alternately reciprocate said cylinders in opposite directions, a pawl pivotally mounted on said frame above each cylinder adapted to contact its cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining the pawls of each cylinder together, and a repeat mechanism comprising a cam rotatably mounted on the loom frame having a semi-circle of a relatively small radius and a semi-circle of a greater radius, a vertically reciprocable support having a split U-shaped upper end having each U-leg thereof attached to each respective lower pawl, and the lower end thereof resting on said cam, whereby when said end rests on the semi-circle of greater radius it will raise up said lower pawls to reverse the direction of rotation of the card

cylinders and when said end contacts the portion of lesser radius on said cam, it will lower the upper pawls to a position to rotate the card cylinders forwards, a ratchet gear attached to said cam, pawl means to rotate said ratchet, means to actuate said pawl means to rotate said ratchet and attached cam, a reducing train of gearing actuated by said cam, and knockoff means for said pawl, means actuated on a complete rotation of the last gear in the reducing train of gearing, after multiple revolutions of said cam, to automatically permit continuous forward movement of the card cylinders. 70 75

11. In a loom, in combination, a jacquard mechanism including a frame, two rotatable card cylinders having cylinder heads rotatable in opposite directions rotatably mounted on said frame, means to alternately reciprocate said cylinders in opposite directions, a pawl pivotally mounted on said frame above each cylinder adapted to contact its cylinder head to cause a quarter forward revolution thereof on each outward movement of the cylinder, a pawl pivotally mounted on said frame below said cylinder adapted to contact the cylinder head to cause a quarter reverse revolution thereof on each outward movement of the cylinder, link means pivotally joining the pawls of each cylinder together, and a repeat mechanism comprising a cam rotatably mounted on the loom frame having a semi-circle of a relatively small radius and a semi-circle of a greater radius, a vertically reciprocable support having a split U-shaped upper end having each U-leg thereof attached to each respective lower pawl, and the lower end thereof resting on said cam, whereby when said end rests on the semi-circle of greater radius it will raise up said lower pawls to reverse the direction of rotation of the card cylinders and when said end contacts the portion of lesser radius on said cam, it will lower the upper pawls to a position to rotate the card cylinders forwards, a ratchet gear attached to said cam, pawl means to rotate said ratchet, means to actuate said pawl means to rotate said ratchet and attached cam, and knockoff means for said pawl means to automatically permit continuous forward movement of the card cylinders.

In testimony whereof I affix my signature,

LOUIS VISCOLOSI.
